UNITED STATES PATENT OFFICE.

JESSE T. RICE, OF GRAND RAPIDS, MICHIGAN, ASSIGNOR, BY DIRECT AND MESNE ASSIGNMENTS, TO AUTOMATIC CAR FENDER AND RAILWAY SUPPLY COMPANY, A CORPORATION OF ARIZONA TERRITORY.

FENDER FOR CARS.

SPECIFICATION forming part of Letters Patent No. 781,740, dated February 7, 1905.

Application filed December 26, 1903. Serial No. 186,640.

To all whom it may concern:

Be it known that I, JESSE T. RICE, a citizen of the United States, residing at Grand Rapids, in the county of Kent and State of Michigan, 5 have invented new and useful Improvements in Fenders for Cars, of which the following is a specification.

This invention relates to a new and useful fender for cars, more particularly adapted to 10 street-cars; and the invention consists in the construction, combination, and arrangement of parts hereinafter described and claimed.

The objects of the invention are, first, to furnish a fender for a car which will not injure a person coming in contact therewith; 15 second, to combine with a suitable frame a fender of a flexible or cushioning material carried thereby which will yield to a person or object falling against it; third, to combine 20 with a yielding surface suitable means for producing such yielding motion and also for preventing reaction; fourth, to combine with a fender a rocking or tipping part which will prevent a person from rolling off the fender 25 after falling thereon; fifth, other objects particularly pointed out in the specification and claims. These objects I accomplish by means of the mechanism illustrated in the accompanying drawings, in which—

30 Figure 1 shows a side elevation of the front end of a car with my improved fender attached in position for use. Fig. 2 shows a front view of a fender constructed in accordance with my invention when attached to a car. 35 Fig. 3 shows a front view of the rocking platform or plate with the flexible surface detached, this rocking platform being placed in part beneath the flexible surface, as shown in Fig. 1. Fig. 4 is a front view of the body 40 part of the fender with the flexible cushioning part removed. Fig. 5 is a detail view of the tension-roller which acts to retain in position and give the cushioning effect to the flexible surface which would receive a person falling 45 upon the fender. Fig. 6 is a side elevation of the front platform of a car and my improved fender folded up against the platform. Fig. 7 is an end view of the tension-roller and

the dog-and-ratchet mechanism for retaining the flexible cushioning part in position after 50 the same has been driven backwardly and downwardly by a concussion of any sort. Fig. 8 is a sectional view of the rocking platform and its support.

Similar letters refer to similar parts 55 throughout the several views.

A designates the front platform of a car constructed in any suitable manner.

B represents the framework of the supporting-body of the fender, by means of which the 60 body of the fender is supported and pivotally connected to the cars, as hereinafter described.

C shows the journal-bearing of the frame-work B.

D D D show the bent portions of the arms 65 L L L, which bent portions engage with the front of the rod B, the rod B forming the bearing on which the said arms L L rock or turn.

E is a plate secured to the arms L L L and together with the arms L and the bar M forms 70 a rocking platform rocking or turning upon the rod B.

F is a front roller carried by the rocking platform and which may be constructed so as to rest upon the car-rails, as shown in Figs. 1 75 and 2.

G shows the journals of the roller F.

H is a flexible connection for raising and lowering the fender, said flexible connection being used in connection with the drum and 80 crank H'.

H shows the flexible connection H wound around the drum, and i i show a bracket supporting the said drum.

a shows the ratchet for retaining the drum 85 in position. Any suitable ratchet may be used, and further description will be unnecessary.

Any other suitable means may be used for raising and lowering the fender.

I is what I call the "yielding support," which 90 yielding support may be constructed of network or any flexible material which will yield to a person falling against the same, which yielding is provided in the example of my invention, shown by means of a roller, which 95 winds up and keeps taut this flexible part I

and which prevents the same from reacting when driven backward, as above described. The flexible support I is adapted to wind around the roller R, the roller R being held 5 in tension by means of a spring, and the roller R is preferably provided with a covering J, so as to protect the flexible material from the weather when it is wound up.

K is a dog engaging with the ratchet U, 10 which dog may be loosened by means of the lever K'.

The bar M, supported on the arms L, forms the rear portion of the tipping platform, and in case a person falls upon the fender the flexible or cushioning surface I will yield, and 15 the person coming in contact with the bar M will tip the same downward, raising the front end of the platform, so as to prevent the person from being thrown off in front of the fender. The arms L may be forked, so as to engage with the plate E E at the points O O, as 20 shown.

The fender-body may be constructed in any suitable manner; but in the drawings I have 25 shown a metallic basket-work, the strips running in one direction being shown by P P, &c., and those in the transverse by P' P', &c. These strips P P, &c., engage or may engage with the rod B', as shown in Fig. 4.

30 b b show the engagement between the frame-rod B and the transverse rod B'.

The car-rails are shown by Q.

The roller R is operated by means of the tension-spring T, which is secured to the 35 transverse rod S'. Said rod S' is square in cross-section at the point S" to prevent the same from revolving. This rod S' is secured to the car by means of the brackets J", J' showing the bearing for the roller R.

40 V is an opening in the covering J, which allows the flexible netting or surface I to be rolled upon the rod R within said casing.

The operation of my invention is as follows: A person or object falling against the yielding 45 surface I will depress the same in the direction of the main body of the fender, said depression being against the operation of the tension-spring T, and if the body is heavy enough the said yielding portion I will continue to yield until it reaches the main body 50 of the fender. The dog K, engaging with the ratchet U, will prevent the spring T from reacting or tending to raise the yielding surface I to normal position, thereby preventing any 55 tendency to throw a person from the fender. If the rocking platform, as hereinafter described, is used, it will be tipped, the bar M being depressed and the front roller F being raised, so as to have a further tendency to prevent 60 a person from being rolled off in front of the fender. As soon as the person is removed from the fender the dog K may be removed from the ratchet U by means of the lever K', and the flexible yielding surface I will immediately assume the position shown in Fig. 1.

When the fender is not in use, the whole may be raised into the position shown in Fig. 6 by means of the parts H and H' or by any other suitable means.

I have described my preferred form of constructing a fender; but it will be understood that various changes may be used without departing from the spirit of the invention. 70

I believe that the use of the flexible or cushioning surface which yields and does not react is entirely new, and I know of no construction using the yielding surface in connection with an unyielding fender. 75

Having thus described my invention, what I claim to have invented, and desire to secure 80 by Letters Patent of the United States, is—

1. In combination with the fender-body secured to the front of a car, a yieldable surface extending above the fender-body, mechanism connected to the yieldable surface to tension 85 the same and means for retaining the mechanism in position after the yieldable surface has been depressed.

2. In combination with the fender-body secured to the front of a car, a yieldable surface 90 extending above the fender-body, mechanism connected to the yieldable surface to tension the same, means for retaining the mechanism in position after the yieldable surface has been depressed, and means for raising and lowering 95 the body and yieldable surface.

3. In combination with the fender-body secured to the front of the car a yielding surface extending above the said fender-body and a sufficient distance therefrom, a roller to which 100 said flexible surface is connected, a spring for operating the said roller and giving tension to said flexible surface, and suitable means for retaining the roller in position after the said flexible body has been depressed, substantially as described. 105

4. In combination with the body of a fender a flexible surface placed above and in front thereof, a roller to which the said flexible surface is connected, a spring adapted to keep 110 the said flexible surface in tension, a ratchet and dog for controlling the said roller and preventing reaction after the same has been tightened by a body falling against said flexible surface. 115

5. In combination with a fender-body pivotally connected to the front of a car, suitable means for raising and lowering the said fender-body and a flexible surface in front of the 120 said fender proper, suitable means for retaining said flexible portion in tension and to allow the same to yield against pressure, and suitable means for preventing the reaction of the said flexible surface.

6. In a car-fender body, the combination of a yieldable surface connected at one end thereof and the other end connected to a tension device above the body, and means for preventing reaction thereof when pressure is applied to the yieldable surface. 125 130

7. In a car-fender body, the combination of a yieldable surface connected at one end thereof and the other end connected to a roller, a tension device for the roller, and means for controlling the reaction of the tension device.

8. In a car-fender body, the combination of a yieldable surface connected at one end thereof and the other end connected to a roller, a tension device for the roller, means for controlling the reaction of the tension device, and a tipping plate connected to the front of the body and actuated by the yieldable surface.

9. In a car-fender body, the combination of a yieldable surface connected at one end there-

of and the other end connected to a roller, a tension device for the roller, means for controlling the reaction of the tension device, a tipping plate connected to the front of the body and actuated by the yieldable surface, and means for raising and lowering the body and yieldable surface.

In testimony whereof I have hereunto set my hand in presence of two subscribing witnesses.

JESSE T. RICE.
